RADIOLYSIS OF MONOOLEFINS
WITH A SENSITIZER

Carl E. Heath, Nixon, and Peter J. Lucchesi, Cranford, N.J., assignors to Esso Research and Engineering Company, a corporation of Delaware

Filed Apr. 29, 1957, Ser. No. 655,912

8 Claims. (Cl. 204—154)

The present invention is concerned with the alkylation of hydrocarbons with monoolefins. It is more particularly directed to the radiation induced reactions of monoolefins with saturated hydrocarbons using as a sensitizer a halogenated hydrocarbon.

In brief compass, this invention proposes a process comprising irradiating a monoolefin reactant containing in the range of 2 through 8 carbon atoms with high energy ionizing radiation, in the presence of 0.1 to 15 wt. percent, based on total feed, of a halogenated hydrocarbon containing 1 through 6 carbon atoms, until at least 0.01 kwh. of radiant energy per pound of product has been absorbed. Preferably the monoolefin is in admixture with 99 to 80 wt. percent, based on total feed, of another saturated hydrocarbon containing from 1 through 20 carbon atoms, whereby alkylation is obtained.

The product of the alkylation comprises in the range of 20 to 90 wt. percent of hydrocarbons having at least two alkyl side chains and the yield is surprisingly high, being above 40 molecules of feed reacting per 100 electron volts of radiant energy absorbed.

The alkylate obtained according to this invention has a very high octane number and is especially useful in gasolines.

The attached drawing of one embodiment of this invention, and the following description will serve to make this invention clear.

This invention is broadly applicable to any monoolefin, whether terminally unsaturated or not, but is most useful with terminally unsaturated monoolefins having from 2 to 8 carbon atoms per molecule, such as ethylene, butene and hexene. Mixtures of monoolefins can be irradiated. These monoolefins can be obtained by any conventional means known to the art, e.g., by the separation of a thermally cracked petroleum fraction such as a light naphtha.

Broadly, any hydrocarbon can be alkylated, according to this invention, with the monoolefins. Most interesting are the ones having from 1 through 20 carbon atoms, such as benzene and its homologs, and especially aliphatics, whether normal or branched, containing 2 through 8 carbon atoms. Mixtures of hydrocarbons can be alkylated. These hydrocarbons can be obtained in any convenient manner, e.g., by separation of crude oils using conventional techniques such as distillation, dewaxing, etc. When carrying out an alkylation reaction, the amount of monoolefin used amounts to preferably 1 to 20 wt. percent of the feed.

The sensitizer used is preferably a halogenated hydrocarbon or alkyl halide containing 1 to 6 carbon atoms, although higher halogenated hydrocarbons may be used. It is preferably vaporous under prevailing reaction conditions, although it can be used in liquid form. It can contain one or more halogen atoms, up to full halogenation. Examples are carbon tetrafluoride, carbon tetrachloride, chloroform, dichloroethane, difluoroethane and bromopropane. The sensitizer can contain two or more different halogen atoms. Examples are dichloro-difluoro methane (Freon 12), trichloromonofluoromethane (Freon 11), and dichlorotetrafluoroethane (Freon 114). The sensitizer molecule can also contain other substituent groups, e.g., a sulfonic, alcohol, carbonyl, peroxide and/or ether group. Examples of the latter are fluoroethane

sulfonic acid, chloropropanol, dibromomethyl peroxide and chloroethyl ketone. The halogenated hydrocarbon is used in an amount in the range of 0.05 to 10 wt. percent, expressed as halogen, based on feed.

The reaction is preferably carried out in the absence of free oxygen, i.e., in the presence of less than 0.5 wt. percent free oxygen; and also preferably in the absence of free hydrogen added to the feed as such. The system can tolerate some inerts such as nitrogen and carbon dioxide, up to about 50 wt. percent. Some inert gases aid in the utilization of the radiant energy and are desirable.

By the term "high energy ionizing radiation" is meant irradiation from terrestrial sources consisting of photons having a wave length less than 50 Å, such as gamma and X-rays; rapidly moving charged or uncharged particles of an atomic or subatomic nature having an energy above 30 ev., such as alpha particles and beta rays; and neutrons. The irradiation is of sufficient intensity that the dose rate is at least 0.01 kwh./hr./lb. of product. This excludes radiation such as cosmic and ultraviolet, which are ineffectual for the purposes of this invention. It is preferred to use essentially gamma or beta radiation because of the safety and ease of control. So far as known, the reaction is not significantly influenced by the type of radiation, but only primarily by the dose rate, total dosage, and conditions under which the radiation is received.

The radiation is obtained from any convenient source, such as charged particle accelerators, e.g., Van de Graaff generators; nuclear reactors; radioactive waste products, e.g., spent fuel elements; and materials especially made radioactive, e.g., cobalt 60 and caesium 137. The use of radioactive isotopes is especially convenient.

The radiolysis of the feed mixture is carried out by exposing it either continuously or batchwise to the radiation. For example, when a nuclear reactor is used, the mixture can simply be flowed through, in, or around the core in suitable conduits, being exposed thereby primarily to neutrons and gamma radiation.

The irradiation of the monoolefins can be carried out in liquid phase, but the vapor phase is preferred. While the pressure can range from 50 to 3000 p.s.i., it is preferably sufficiently low to permit vapor phase conditions to be realized. The temperature is preferably in the range of 100° to 800° F. The dosage received is preferably at least 0.01 kwh./lb. of product. Excessive dosages are to be avoided and usually not more than 1.0 kwh./lb. of product will be necessary. For best results, the dose rate for all types of radiation, whether mixed or pure, should be at least 0.01 kwh./hr./lb. of product to produce a favorable rate of reaction. It is usually not necessary to use a dose rate above 10 kwh./hr./lb.

The product obtained from alkylation of hydrocarbons in the preferred embodiment of this invention, has normally 5 to 20 carbon atoms and boils in the range of 90° to 430° F. For the above dosages, this alkylate can be obtained in yields in the range of 2 to 30 wt. percent, based on total feed. Because of the surprising degree of branchiness in the product, it has a high octane rating, usually above 90 Research Clear, and is especially suited for use in or as a gasoline.

In the drawing, an olefin-paraffin mixture is supplied by line 1 to a radio-alkylation zone 2. Zone 2 can comprise any convenient radiation source, such as a nuclear reactor, wherein mixed neutron and gamma ray irradiation is obtained. Line 3 supplies to line 1 a small amount of an alkyl halide sensitizer according to the teachings of this invention. After the radio-alkylation is completed to the extent desired, the product is transferred by line 4 to a separation zone 5. In separation zone 5, any further treatment of the alkylate can be made as desired. For example, a simple distillation can be carried out to remove

inreacted hydrocarbons which can be recycled, if desired, by line 6. The alkylate product is removed by line 7.

EXAMPLE 1

An isobutane-propylene (8/1 mole ratio) mixture was converted in the presence and in the absence of a fluoro hydrocarbon sensitizer. The isobutane-propylene mixture, with the addition of 1 wt. percent of dichloro-difluoro methane (Freon 12), was converted in high yields to C_6 and C_7 isoparaffins when irradiated at 100° F. with gamma radiation obtained from a cobalt 60 source. The source was in the form of a two-inch O.D. hollow pipe and had a rating of about 3000 curies. The radiation was continued at a rate of about 1.0 megaroentgen per hour (one megaroentgen equals approximately 3.62 B.t.u.'s per pound of radiation), until a dosage of 65 megaroentgens had been received. The radiation yield in terms of two molecules of feed reacting to form one molecule of product, was 43 molecules per 100 electron volts. The yield was 135 wt. percent based on olefin.

When the isobutane-propylene mixture was irradiated in the absence of the fluorocarbon, the radiation yield on the above basis was 26 feed molecules reacted per 100 ev., the radiation being carried out on the same conditions. The product contained 56% of isoparaffins and the remainder of C_5+ liquid product was C_6 dimer.

Table I presents the results of these irradiations and shows the surprisingly high yield of branchiness obtained in the irradiation of the mixture containing the dichloro-difluoro methane sensitizer.

Table I

Compound	Wt. Percent of Isoparaffin Fraction	
	With Freon 12 ¹	Without Freon 12 ²
C_5	0.3	
2,2-DMB	7.4	2.3
2-MP, 2,3 DMB ³	6.9	43.3
3-MP	0.4	11.6
2,4-DMP, 2,2-DMP ³	80.0	25.8
2,3-DMP, 3,3-DMP ³	3.1	17.4
2-MH, 3-MH ³	1.2	
3-EP	.7	

¹ Isoparaffin fraction is 90 wt. percent of total C_6+ product.

² Isoparaffin fraction is 56 wt. percent of total C_6+ product.

³ GLPC (Gas-Liquid Partition Chromatography) used to obtain these results does not distinguish between these isomers.

NOTE.—Title abbreviations used in tables: DMB—Dimethyl butane; MP—Methyl pentane; DMP—Dimethyl pentane; MH—Methyl hexane; EP—Ethyl pentane.

EXAMPLE 2

A mixture of 8 moles of isobutane and one mole of propylene was irradiated in the source described in Example 1 at a temperature of 500° F. and a pressure of 800 p.s.i. in the vapor phase. The dose rate was 1.5×10^6 roentgens per hour of gamma radiation, and the total dosage received was 9.3 megaroentgens. One run was carried out in the presence of 1.0 wt. percent chloroform as a sensitizer, and the other was carried out in the absence of a sensitizer. Table II gives the results of these irradiations, and Table III gives an inspection of the products.

Table II

	Yield, Wt. Percent C_6+ , on—		Radiation Yield, Molecules Feed Reacted/100 ev.	C_6-C_7 Isoparaffin/ C_6+
	Olefin Charged	Olefin Consumed		
CHCl ₃	108.2	210.4	244	45.3
None	53	.95	150	28.6

Table III

Compound	Yield, Wt. Percent on Iso C_5 -Iso C_7	
	With CHCl ₃	Without CHCl ₃
IC ₃		
2,2-DMB	1.8	1.4
2-MP, 2,3 DMB ¹	4.0	7.0
3-MP	2.4	19.2
2,4-DMP, 2,2-DMP ¹	76.8	62.5
2,3-DMP, 3,3-DMP ¹	13.9	5.9
3-MH, 2-MH ¹	.9	2.8
3-EP	.2	.7

¹ GLPC does not distinguish between these compounds.

It can be seen that the chloroform had an appreciable effect on the yield and on the type of products obtained from the radio-alkylation.

It was expected that conventional alkylation catalysts might also be used as sensitizers. The use of hydrogen fluoride in alkylation tests of the same nature as above, both in the liquid and in the vapor phase, proved unsuccessful.

COMPARATIVE EXAMPLE 1

A mixture of 8 moles of isobutane and 1 mole of propene was irradiated in the liquid phase at 150° F. in the source described in Example 1, until 65 megaroentgens of radiation had been absorbed. Table IV shows that no significant improvement was noted with the hydrogen fluoride sensitizer, as compared to radio-alkylation in the absence of hydrogen fluoride.

Table IV

	C ₅ + Yield		Radiation Yield, Feed Molecules Reacted/100 ev.
	Wt. Percent on Olefin Fed	Wt. Percent on Olefin Consumed	
With 1 wt. percent HF	39.1	83.7	12.6
Without	88	49	13.0

COMPARATIVE EXAMPLE 2

A mixture of 8 moles of isobutane and 1 mole of propylene was irradiated in the vapor phase in the source described in Example 1, and 500° F. until 9.3 megaroentgens of radiation had been absorbed. Table V shows that the presence of 1.0 wt. percent of hydrogen fluoride as compared to a run made in the absence of hydrogen fluoride, did not give significantly different results.

Table V

	C ₅ + Yield		Radiation Yield, Feed Molecules Reacted/100 ev.
	Wt. Percent on Olefin Fed	Wt. Percent on Olefin Consumed	
With 1 wt. percent HF	51	55.5	116
Without	53	95	150

COMPARATIVE EXAMPLE 3

Table VI shows a comparison between the present sensitized radio-alkylation process, and the sulfuric acid alkylation process known to the prior art.

5
Table VI

Process	Radiation + Freon 12	Catalytic H ₂ S ₂ O
Phase	Liquid	Liquid
Conditions:		
iC ₄ /C ₂ = Mole Ratio	8/1	6/1
Temperature, ° F.	150	55
Pressure, atm		
Other	65 MR	
C ₄ + Yield, Wt. percent on C ₃ -Feed	135	200
Product Composition, C ₆ + Isoparaffins, Wt. percent on C ₆ +		
1C ₆	.3	3.4
2,2-DMB	6.6	
2-MP, 2,3-DMB	6.2	6.1
3-MP	.4	
2,4-DMP, 2,2-DMP	71.6	17.9
2,3-DMP, 3,3-DMP	2.8	26.9
2-MH, 3-MH	1.1	
3-EP	.6	

It can be seen that the product distribution as well as the yield of isoparaffins of the present radio-alkylation process are substantially different from the results obtained by the prior art's sulfuric acid process.

The invention having been described, what is sought to be protected by Letters Patent is succinctly set forth in the following claims.

What is claimed is:

1. A process comprising irradiating a monoolefin reactant containing 2 to 8 carbon atoms in admixture with 99 to 80 wt. percent of a saturated hydrocarbon containing from 1 to 20 carbon atoms with high energy ionizing radiation equivalent to at least 30 electron volts in the presence of 0.1 to 15 wt. percent, based on total feed, of a halogenated hydrocarbon containing 1 to 6 carbon atoms, until in the range of 0.01 to 1.0 kwh. of radiant energy per pound of product has been absorbed, and thereby obtaining a product comprising in the range of 20 to 90 wt. percent of hydrocarbons with at least 2 alkyl side chains.

2. The process of claim 1 wherein the temperature is in the range of 100° to 800° F. and the radiation is carried out substantially under vapor phase conditions.

3. The process of claim 1 wherein said product boiling in the range of 90° to 430° F. amounts to 2 to 30 wt. per-

cent, based on total feed, and has a Research Clear octar number above 90.

4. A process comprising irradiating a terminally unsaturated monoolefin having from 2 to 8 carbon atoms in admixture with 99 to 80 wt. percent of a saturated aliphatic hydrocarbon having from 2 to 8 carbon atoms with high energy ionizing radiation equivalent to at least 3 electron volts at a rate in the range of 0.01 to 1 kwh./hr./lb. of product at a temperature in the range of 100° to 800° F., until in the range of 0.01 to 1.0 kwh./lb. of product of radiant energy has been absorbed, the reactants containing 0.1 to 15 wt. percent of an alkyl halide sensitizer containing from 1 through 6 carbon atoms, and thereby obtaining a product comprising in the range of 20 to 90 wt. percent of hydrocarbons with at least 2 alkyl side chains.

5. The process of claim 4 wherein the alkyl halide is dichloro-difluoro methane, the monoolefin is propylene and the other hydrocarbon is isobutane.

6. The process of claim 4 wherein the alkyl halide is chloroform, the monoolefin is propylene, and the other hydrocarbon is isobutane.

7. Process as defined by claim 1 wherein at least 1 weight percent of said halogenated hydrocarbon is present based on feed.

8. The process of claim 4 wherein the reactants contain at least 1 weight percent of said alkyl halide sensitizer.
